UNITED STATES PATENT OFFICE.

FRANKLIN A. REECE, OF MANCHESTER, AND JOHN KIEWICZ, OF BOSTON, MASSACHUSETTS, ASSIGNORS TO THE REECE BUTTON HOLE MACHINE COMPANY, OF BOSTON, MASSACHUSETTS, A CORPORATION OF MAINE.

SEWING-MACHINE.

1,088,624.

Specification of Letters Patent.

Patented Feb. 24, 1914.

Application filed May 8, 1913. Serial No. 765,212.

To all whom it may concern:

Be it known that we, FRANKLIN A. REECE, a citizen of the United States, residing at Manchester, county of Essex, State of Massachusetts, and JOHN KIEWICZ, a citizen of the United States, residing at Boston, county of Suffolk, State of Massachusetts, have invented an Improvement in Sewing-Machines, of which the following description, 10 in connection with the accompanying drawing, is a specification, like characters on the drawing representing like parts.

This invention relates to sewing machines and has for one of its objects to provide a 15 novel and simple mechanism for operating the shuttle whereby the number of parts is reduced and a construction is provided which enables the machine to run at a high speed without vibration.

20 While our invention is applicable to various types of sewing machines, it is particularly applicable to machines of that type in which the needle is sustained by a needle bar that operates in a horizontal plane 25 beneath the bed frame of the machine, as is usually done in a so-called finisher machine, and, therefore, we have illustrated the invention as it would be applied to a machine of this type.

30 In order to give a specific illustration of the invention, we have chosen to show it as it would be applied to a finisher machine of the type shown in patent to Kiewicz, No. 1,047,537, dated December 17, 1912. We 35 wish to state, however, that the invention is not limited to use in this particular type of machine.

Referring now to the drawings, Figure 1 is a side view of a finishing machine such 40 as shown in said Kiewicz Patent No. 1,047,537, with a portion broken out to illustrate the invention; Fig. 2 is an end view of the bed plate with a part broken out to illustrate the invention; Fig. 3 is a section on the 45 line α — α , Fig. 2; Fig. 4 is an under side view of the machine.

We have shown at 1 the bed plate of the machine beneath which is journaled the usual driving shaft 2 by which the parts are 50 driven, said shaft being operated from a loose pulley 3 thereon by suitable clutch mechanism designated generally by 4 which it will not be necessary to describe at all in detail.

The needle 5 is secured to a needle bar 6 55 which reciprocates in a swinging frame 7 that is given its lateral movement by means of the connection 8 operated from the switch cam 12 on the main shaft 2, as usual in machines of this class. The needle bar and 60 needle operate directly underneath the top of the bed plate and in a horizontal direction. The needle bar receives its actuation from a crank disk 9 fast on the shaft 2 by means of a connecting rod 10 which is 65 mounted on a stud 11 carried by a block 130 secured to the needle bar, all as shown in said Patent No. 1,047,537. The rotation of the shaft 2 will reciprocate the needle bar 6 and the latter will be given a lateral movement for the operation of the stitches by the 70 switch cam 12.

Finishing machines of the above-described type have as a part thereof benders for forming bends in the work, thus enabling 75 blind stitches to be formed. The bender is shown at 13 and is mounted on a swinging arm 14 which is illustrated as pivoted to the frame at 15 and is given its vibrating movement by means of a cam on the main shaft 80 2, all as illustrated in said Patent No. 1,047,537.

300 is a presser-foot carried by a vibrating arm 31 also pivoted to the frame at 15, said arm having an extension 32 which cooperates with the clutch mechanism in such a way that when the clutch is released the presser-foot is elevated. This feature is also illustrated and described in the aforesaid patent.

Cooperating with the needle in the operation of forming the stitch is a shuttle, as usual in sewing machines of this type, said shuttle not being shown herein as it forms no part of our invention. This shuttle is 95 sustained by an oscillatory shuttle carrier which is mounted to turn in a block 18 secured beneath the bed plate and which is provided with a depending shaft or pin 19 carrying at its lower end an arm 48 provided with a stud 47 playing in a slot 46 of an oscillatory member 44 which is pivoted at 45.

The parts thus far described are or may be substantially as shown in the aforesaid patent, and as the operation will be readily 105 understood, no further description thereof is deemed to be necessary.

In our present invention we provide a

simple and novel mechanism for operating the shuttle which consists of means for connecting the oscillatory member 44 directly to the needle bar, so that the reciprocations 5 of the needle bar are transmitted directly to the shuttle carrier and thus to the shuttle. We accomplish this end herein by providing the pin 11 to which the actuating link 10 is secured with an extension 20 and which is 10 received in an aperture in the end 21 of a link or connecting member 22, the other end of which is pivotally connected to the oscillatory member 44, as shown at 23. The pin or projection 11 is provided with a 15 guiding flange 24, the upper edge of which is received in a groove 25 formed in the under side of a guiding member 26 secured to the bed plate, said guiding flange 24 serving to maintain the pin 11, and consequently 20 the end of the connecting member 10, in a right line. It will be remembered that the needle bar has a lateral movement, and this lateral movement is permitted by a sliding connection between the block 130 25 and the pin 11. The projection 20 is shown as provided with a head 30 which is received behind guiding lips 33 secured to the end wall 34 of the bed frame, said guiding lips 33 acting in conjunction with the guiding flange 24 and groove 25 in holding the parts in a correct right line during their reciprocating movement. With this construction it will be noted that there is a direct and single connection between the pin 11 by 30 which the needle bar is actuated and the oscillatory member 44, this single connection comprising simply the link 22. The shuttle is, therefore, directly operated from the needle-bar-actuating mechanism and no 35 separate device or set of devices for actuating the shuttle from the main shaft 2 is required, as is illustrated in the before-mentioned patent. This construction reduces 40

the number of parts in the machine materially and provides a construction which 45 can be operated at high speed without any inconvenience.

While we have illustrated herein one embodiment of our invention, we do not wish to be limited to the constructional features 50 shown.

Having fully described our invention, what we claim as new and desire to secure by Letters Patent is:

1. In a sewing machine, the combination 55 with a bed plate frame, of a horizontally-reciprocating needle-bar beneath said bed plate, a pin extending laterally from the needle bar, means on the frame forming a guide for the end of the pin, actuating 60 mechanism connected to said pin for actuating the needle bar, a shuttle carrier, and means connected to said pin for actuating the shuttle carrier.

2. In a sewing machine, the combination 65 with a bed plate frame, of a horizontally-reciprocating needle-bar beneath said bed plate, a pin extending laterally from said needle-bar, guiding means on the frame for receiving and guiding the end of the pin, a 70 driving shaft, a connecting rod connecting said shaft and pin, a shuttle carrier, an oscillatory member connected thereto, a link connecting said oscillatory member to said pin, the latter having a guiding flange 75 thereon between said link and connecting rod, and the bed frame having a guiding groove to receive said flange.

In testimony whereof, we have signed our names to this specification, in the presence 80 of two subscribing witnesses.

FRANKLIN A. REECE.
JOHN KIEWICZ.
